UNITED STATES PATENT OFFICE.

VALDEMAR WILMING, OF COPENHAGEN, DENMARK, ASSIGNOR TO GÜNNAR KOEFOED,
OF COPENHAGEN, DENMARK.

DEVICE FOR MIXING AMALGAM FOR TOOTH FILLINGS AND STOPPINGS.

Application filed March 16, 1927, Serial No. 175,881, and in Germany March 17, 1926.

This invention relates to a device for mixing the amalgam for tooth fillings or stoppings. Hitherto, this mixing was effected by rubbing together the metal powder and the mercury in a mortar, an operation which is very tedious and requires about ten minutes. Machines for mixing the amalgam have already been proposed, which were adapted to be driven by the flexible shaft of a dental drilling machine or the like, but the constructions suggested require a considerable amount of power or are heavy and unwieldy, whereas such a device should be capable of being conveniently held in the hand, and should not require any appreciable power for its movement.

According to the present invention oscillations are imparted to a pot by a rod connected thereto and to a transverse shaft, which rod carries at its lower end a body open at the bottom which is oscillated in such a manner by a pin eccentrically connected with a rotary shaft and engaging with the body with some freedom of movement, that the pin is capable of producing the movement of the pot in jerks.

The device according to the invention is illustrated in the accompanying drawing, wherein:

30 Figure 1 shows an external view, partly in section.

Figure 2 shows a partial view of the device turned through 90° relatively to Figure 1.

35 Figure 3 shows a modified form of construction, and

Figure 4 shows a detail of Figure 3.

40 *a* is a horn pot having a screwed on cover *b*. Into the pot is screwed or cemented a rod *c* which is rigidly connected to a transverse shaft *d*. This shaft is mounted in a box *e* of which the cover is provided with a longitudinal recess extending transversely to the shaft *d* in order to permit of an oscillatory movement of the rod *c* and thus of the pot *a*.

45 The rod extends downwardly into a trough-shaped body *f* which is open at the bottom. With this engages a pin *g* mounted eccentrically on a disc *h*. The parts *f*, *g*

and *h* are enclosed in a box *i* on which is screwed the box *e* by means of a flange *k*.

The disc *h* is rigidly connected to a shaft *l* which is passed through the hollow hand piece *m*, this hand piece being screwed to the box *i*.

Within the hollow extension *n* of the hand piece *m* the shaft *l* is provided with a driving member *o* adapted to be connected to a flexible shaft, for example, of a drilling machine.

The method of imparting an oscillatory movement to the pot *a* is hereinbefore described only by way of example. It may be modified in various ways according to the driving means which are available. For example, Figures 3 and 4 show a form of construction in which the driving shaft for the pot is arranged horizontally and the rod *c'* is formed as a fork with which engages the eccentric pin *g'*.

I claim:

1. In a device for mixing amalgam for tooth fillings and stoppings, a pot for receiving the amalgam components, a rod integral with the said pot and carrying a transverse shaft swingingly journaled in a support, a body integral with the end of the said rod and provided with a longitudinal groove, and a pin adapted to rotate in the said groove with some freedom of movement and thereby rocking the pot in jerks.

2. In a device for mixing amalgam for tooth fillings and stoppings, a pot for receiving the amalgam components, a rod integral with the said pot and carrying a transverse shaft swingingly journaled in a support, a body integral with the end of the said rod and provided with a longitudinal groove, a pin adapted to rotate in the said groove with some freedom of movement and thereby rocking the pot in jerks, a hollow handle connected with the said support, a shaft rotatable in the said handle and eccentrically connected with the said pin, and means for connecting the said rotatable shaft with the shaft of a dental engine.

In testimony whereof I affix my signature.

VALD. WILMING.
